RACK INSERTING MECHANISM

Original Filed April 25, 1936

UNITED STATES PATENT OFFICE

2,343,043

RACK INSERTING MECHANISM

William F. Brügmann, Evanston, Ill.

Original application April 25, 1936, Serial No. 76,454. Divided and this application July 11, 1940, Serial No. 345,016

10 Claims. (Cl. 22—84)

This invention relates in general to printing plate mounting devices, such as those employing the type of rack adapted to be secured in grooves therein disclosed in my co-pending application Serial No. 76,454, filed April 25, 1936, and issued August 6, 1940, as U. S. Letters Patent No. 2,210,749, and it relates more particularly to the apparatus for inserting such racks. The present application is a division of said Patent No. 2,210,749.

While the instant invention is clearly applicable to printing press plate cylinders and to plate supporting bases for flat bed presses, it is shown and described herein in conjunction with the former, since its advantages in such an installation are more readily apparent.

The prior art discloses the cutting of helical grooves in the circumferential surface of printing press cylinders within which register hooks are adapted to be mounted, and the provision of a rack or racks therein with which driving means, such as gears or worms, in the hooks may cooperate to move the hooks longitudinally of the grooves into and out of clamping engagement with the usual printing plates. These prior art racks, however, and the methods employed in mounting them in the grooves in the cylinders have certain practical disadvantages which it is the purpose of the instant invention to overcome.

Heretofore the racks have been pushed or pulled longitudinally into T-slots cut adjacent the bottom of the grooves. Since the racks are subjected to great strain by the driving elements of the hooks both in their initial registering movements, and during a run by the action of the impression cylinders on the printing plates, undue wear of certain portions of the racks and breakage of some of the teeth thereof naturally follow in the course of time. In the prior art devices it is then necessary to remove the entire rack from the full length of the groove, even though but a small portion thereof has been damaged. To do this, the plate cylinder must be taken out of the press and shipped to the factory where the necessary tools and equipment are available to do the work, and, in the meantime, the press is completely out of commission.

A principal object of my invention, therefore, is the provision of novel apparatus for inserting a rack in a groove in a printing plate supporting member, such as a plate cylinder, from the top of the groove, and riveting it in the bottom portion thereof.

Numerous other objects and advantages of the

invention will be apparent as it is better understood from the following description, which, when taken in connection with the accompanying drawing, discloses a preferred embodiment thereof.

5 In the drawing,

Figure 1 is an elevational view, with parts broken away, of a printing plate cylinder and apparatus for inserting racks, embodying the features of the instant invention, in helical grooves in the cylinder;

10 Figure 2 is a front elevational view, with the upper portion in vertical section, of the tool holding device of Fig. 1;

15 Figure 3 is a side elevational view, partly in section, of the lower portion of the device of Fig. 2 in operative position in a groove of the cylinder;

20 Figure 4 is a detail rear elevation of the riveting roller; and

25 Figure 5 is a detail vertical section of a portion of the printing plate cylinder showing a groove having a rack mounted therein.

Referring more particularly to the drawing, 30 reference numeral 21 indicates a printing press plate supporting cylinder of well-known construction having end bearing members 22 (Fig. 1). A plurality of spaced, parallel, helical grooves 23 are cut in the circumferential surface of the cylinder 21 in the usual manner, and are preferably disposed at an angle of approximately 45 degrees to the longitudinal axis of the cylinder.

The grooves 23 are constructed to receive any 35 suitable form of plate holding devices, such as the printer's register hook disclosed in my prior U. S. Letters Patent No. 2,124,728, issued July 26, 1938, and are provided on each side adjacent the top with longitudinal, under-cut recesses 24 (Figs. 3 and 5) within which the locking elements of the plate holding devices (not shown) are adapted to be positioned. At their lower ends, the side walls of the grooves 23 are cut back or outwardly at a slight angle and for a

40 short distance at 25 to provide a slightly laterally enlarged recess at the bottom of the grooves

45 within which are mounted racks 26 adapted to be engaged by the driving gears of the printer's register hooks.

The racks 26 are provided with teeth 27 on their upper surfaces formed integrally therewith, and with longitudinal, marginal recesses 28 on either side of and extending slightly below the root line or bottom portion of the teeth 27 (Fig. 5). When the racks 26 are secured in place in

the bottom of the grooves 23, these marginal recesses 28 form gutters along the sides of the teeth 27 for the accumulation and drainage of foreign matter, and also facilitate the securing of the racks within the grooves 23 in a manner to be later described. The racks 26 are also preferably provided with a substantially centrally located, longitudinal recess or groove 29 in the bottom surface thereof for a purpose which will be explained hereinafter.

For positioning the racks 26 in the grooves 23 and securing them in place, after the grooves have been cut in the printing plate supporting member 21, the following mechanism is provided. Any suitable device may be employed upon which to mount the printing plate supporting member, this being shown in Fig. 1 as an ordinary planer, indicated generally by reference numeral 31. The bed of the planer 31 is provided with the usual driving rack 32 on the under side, by means of which it is oscillated longitudinally (sideways in Fig. 1) in well-known manner, and with the usual longitudinal T-slots 33 in the upper surface thereof. A pair of trunnion supporting members 34 are secured to the bed of the planer 31 by the usual T-bolts 35 mounted in T-slots 33. The trunnions 34 are adapted to receive the bearing members 22 of the plate cylinder 21 to rotatably support the cylinder on the planer bed with its axis disposed longitudinally thereof.

If it is desired, a tensioning means of some sort may be provided to resiliently urge the cylinder 21 to rotate in a clockwise direction, as viewed from the rear of the planer 31, or the right of Fig. 1, for a purpose to be later described. Such a tensioning means is shown in Fig. 1 as comprising a coil or clock spring device 36, mounted on the bed of the planer 31, and having one end of a flexible strap or cable 37 secured thereto, the other end of which is adapted to be wound around and secured in any suitable manner to one of the bearing members 22 of the cylinder 21. A handle 38 may be provided on the tensioning device 36 for winding up and controlling the operation of the spring therein.

The planer 31 is provided with the usual uprights 41, between which the bed is adapted to reciprocate, cross-brace 42 mounted between the uprights 41 for vertical adjustment, cross-slide 43 mounted for lateral adjustment on the brace 42 by screw 44, and tool holder 45 pivotally mounted at 46 on the slide 43 for forward swinging movements only relative thereto. A rack inserting tool, indicated generally by reference numeral 48, is adapted to be secured in any suitable manner, as by a U-clamp member 49, to the forward face of the tool holder 45.

Referring to Figs. 2 to 4, the rack inserting tool 48 comprises a cylindrical body portion 51, which is adapted to be engaged by the clamp 49. The body portion 51 is provided with an axial bore 52, having a decreased threaded portion 53 at its upper end. An internally and externally threaded collar or pressure member 54 is screwed into the reduced threaded portion 53 of the bore 52, and is provided with an angular head portion 55. A rod 56 is disposed within the longitudinal bore 52 of the body portion 51, and is threaded adjacent its upper end for engagement with the inner threads of the collar 54. The rod 56 terminates at its upper end in an angular head portion 57. A collar 58 is disposed within the bore 52 surrounding the rod 56, and is pressed upwardly against the lower end of the collar 54 by a compression coil spring 59, which also sur-

rounds the rod 56, and is disposed within the bore 52. The lower end of the coil spring 59 abuts against the upper end of a vertical cylindrical extension 61 forming a part of a tool carrier, indicated generally by reference numeral 62.

The cylindrical extension 61 is disposed within the lower part of the bore 52, and is provided with a bore 63 through which the lower end of the rod 56 extends. The extension 61, and consequently the tool holder 62, is held against rotation relative to the body portion 51 in any one of a plurality of predetermined positions by a setscrew 64, which is mounted in the cylinder 51, and is adapted to engage within a selected one of a plurality of grooves 65 in the outer surface of the extension 61.

The grooves 65 may be spaced around the circumference of the extension 61 for a purpose which will be hereinafter explained. Each of these grooves is of such a width that the inner end of the screw 64 will firmly engage its side walls, and is of such a length as to permit limited vertical movement of the tool holder 62 relative to the body portion 51.

Referring more particularly to Fig. 3, it will be seen that the tool holder 62 comprises a rounded rear end portion 66, disposed immediately below the extension 61, and a flattened forwardly extending yoke portion 67. The rear portion 66 is provided with a vertical bore 68, which is co-axial with the bore 63 in the extension 61. A cylindrical tool carrying member 69 is mounted for sliding movement within the bore 68. The upper end of the tool carrier 69 is adapted to be engaged by the lower end of the rod 56. The tool carrier 69 is held against rotation relative to the tool holder 62 by a setscrew 71 extending through the rear wall of the latter and engaging within a short vertical slot or groove 72 in the surface of the tool carrier 69. The slot 72 is of sufficient length to permit a certain amount of vertical movement of the tool carrier 69 relative to the tool holder 62.

It will be readily apparent that the cylindrical members 61 and 69 may be given an angular cross section in order to eliminate the necessity of using setscrews 64 and 71 to prevent rotation of these members. If this is done, however, other means must be provided for limiting the vertical movement of these members.

The lower end of the tool carrier 69 is formed to provide a narrow depending yoke portion 73 (Figs. 3 and 4). A double bladed riveting roller 74 is mounted on the lower end of the tool carrier 69, with the yoke portion 73 straddling the center portion thereof, and is removably held in place by a horizontally disposed pin 75 extending through the lower ends of the yoke 73. Each of the blades of the riveting roller 74 is provided with a plurality of circumferentially spaced teeth 76. The teeth 76 are triangular in radial cross section (Fig. 4) with their outer surfaces being disposed at a lesser angle to a vertical plane than are their inner surfaces. The purpose of so shaping the teeth of the riveting roller 74 will be later described. A pressure roller gear 77 is rotatably mounted on a cross shaft 78 extending through and supported by the lower forward end of the yoke 73. Horizontal, forwardly extending guide bars 79 are mounted at their rear ends on the outer ends of the shaft 78, and are held against the outer surfaces of the yoke by retaining nuts 81 threaded on the outer ends of the shaft 78.

The above described mechanism is used to insert and secure the racks 26 within the bottom portion of the grooves 23 in the cylinder 21 in the following manner:

The cylinder 21 is first mounted in the trunnions 34 with its axis extending longitudinally of the bed of the planer, as shown in Fig. 1. The rack inserting tool 48 having been secured to the tool holder 45 of the planer and positioned directly above the axis of the cylinder 21, the setscrew 64 is unscrewed to permit the setting of the tool holder 62 at the same angle to a vertical plane defined by the axes of the cylindrical body portion 51 and the plate-holding cylinder 21, as the grooves 23 are disposed relative to the same plane. For this reason a plurality of grooves 65 are provided in the outer surface of the extension 61 of the tool holder 62. Since it is substantially universal practice to cut the grooves 23 in the cylinder 21 at an angle of 45 degrees to the axis of the cylinder, only one such groove 65 may be actually necessary.

The bed of the planer is run forward sufficiently to clear the uprights 41, and one end of a rack 26 is placed in the end of one of the grooves 23, and manually riveted or otherwise secured therein. In their initial form before they are mounted in the grooves 23, the side walls of the racks 26 are vertically disposed, and the racks are of such a width as to permit them to readily slide downwardly into the grooves 23. After they have been loosely positioned in the bottom of the grooves, downward and outward pressure on their upper surfaces adjacent their outer edges will force a certain amount of metal into the angular recesses 25 to firmly secure them in the bottom of the grooves, as shown in Fig. 5.

One end of a rack 26 having been secured in the rear end of one of the grooves 23 by hand, such portion of the groove 23 is brought beneath the guide roller 77, and the latter is lowered into this groove. The rack 26 extends loosely in front of the guide roller 77 and is maintained in line with the groove 23 by the forwardly extending guide bars 79. The initial cross vertical adjustment of the riveting tool 48 down into the selected groove 23 is had by moving the tool holder 45. Any desired degree of downward pressure may be maintained on the tool holder 62, and consequently the guide roller 77, by adjusting the collar 54 to vary the tension in the coil spring 59.

The arrangement of these parts is such that the guide roller 77 is resiliently and not positively held against vertical movements. Since the cylindrical body portion 51 is rigidly held by the clamp 49, vertical movement of the riveting roller 74 is positively prevented by the rod 56 abutting against the tool carrier 68. This rod provides a means of micrometric adjustment for the riveting roller 74.

The bed of the planer 31 is now moved rearwardly (to the right in Fig. 1), which carries the cylinder 21 past the riveting tool 48. Since the guide roller 77 is positioned in the selected groove 23, the cylinder 21 will be rotated by the guide roller as it is moved rearwardly. To assist in this rotative movement of the cylinder 21, the tensioning means 36 may be employed as above described. As the cylinder 21 is moved past the riveting tool 48, the guide roller 77 insures proper positioning of the rack 26 in the bottom of the groove 23, since the teeth of the roller are formed to accurately mesh with those of the rack. For

this reason, the guide roller 77 may also function as a final forming tool for the teeth 27 of the rack. If it is desired, a suitable shoe may be secured to the tool holder 62 in advance of the guide roller 77 to relieve the guide roller from the side pressure developed in rotating the cylinder 21.

The riveting roller 74 is positioned vertically so that its teeth 76 will dig into the upper side surfaces of the rack defined by the recesses 25. The shape of the teeth 76 is such that this will result in a sideward deflection of some of the metal into the inclined recesses 25 at the bottom of the groove 23. The particular shape of the riveting roller 74 will also insure against any damage being done to the teeth 27 of the rack in this riveting operation.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A device for inserting a toothed rack in a groove in a printing plate supporting member, comprising means for supporting said member, means for engaging the teeth of said rack to seat the latter in said groove and to insure against deformation of said teeth during such operation, said first and second means being movable relative to each other longitudinally of said groove, and means for displacing desired longitudinal edge portions of said rack without altering the shape of said teeth to rigidly secure the rack in said groove.

2. A device for inserting a toothed rack in a groove in a printing plate supporting member, comprising means for supporting said member and moving it longitudinally of said groove, means for engaging the teeth of said rack to seat the latter in said groove as the plate supporting member is moved by said first means and to maintain said teeth in their original shape during such operation, and means adjustable relative to said last means for displacing desired longitudinal edge portions of said rack without altering the shape of said teeth to rigidly secure the rack in said groove.

3. A device for inserting a rack in a helical groove in a printing plate supporting cylinder, comprising means for rotatably supporting said cylinder, and means for seating the rack in the groove and displacing desired portions thereof to rigidly secure the rack to said cylinder, said first and second means being movable relative to each other axially of said cylinder, and said second means being engageable with said groove to cause rotation of said cylinder during relative movement of said first and second means to maintain the groove and that portion of the rack being inserted therein in proper relative relationship.

4. A device for inserting a rack in an undercut, helical groove in a printing plate supporting cylinder, comprising means for rotatably supporting said cylinder and axially moving the same, and means adjustable relative to said first means for engagement with said groove and normally stationary relative thereto for seating the rack in the groove and displacing portions thereof into the under-cut portions of said groove to rigidly secure the same therein, said second

means also causing said cylinder to rotate as it is moved axially by said first means to maintain engagement with said groove.

5. A device for mounting a metal strip in a groove, comprising means for guiding said strip into and properly positioning the same in the bottom of said groove, and means movable with said first means and adjustable relative thereto for forcing portions of said strip against a wall of said groove to rigidly secure the strip in the groove.

6. A device for mounting an elongated metal strip in the bottom of a groove, comprising a member for seating said strip in the bottom of said groove, and a second member operable in conjunction with said first member for rigidly securing said strip in the bottom of said groove by upsetting portions of the strip against the side walls of the groove.

7. In a device of the class described, a supporting member, a tool holder supported by and mounted for limited movement relative to said member, a second tool holder supported by and mounted for limited movement relative to said first tool holder, and means mounted on said supporting member for adjusting said second tool holder relative thereto and relative to said first tool holder.

8. In a device of the class described, a supporting member, a tool holder supported by and mounted for limited movement relative to said member, spring means urging downward movement of said tool holder relative to said member and resiliently resisting upward movement of

said tool holder relative to said member, a second tool holder supported by and mounted for limited movement relative to said first tool holder, and means for superseding the action of said spring means in regard to said second tool holder to adjust the latter relative to said supporting member and to limit upward movement of said second tool holder against the action of said spring means.

10. A tool for riveting racks into the bottom of under-cut grooves in a printing plate supporting member, comprising teeth adapted to straddle the teeth on a rack, which are centrally disposed and upstanding from the top of the rack, the teeth on the tool being triangular in cross section with the outer surfaces at a steeper angle than the inner surfaces, whereby downward pressure on the tool will displace portions of said rack into the under-cut portions of its associated groove.

15. 10. A device for inserting a rack in a helical groove in a printing plate supporting cylinder, comprising means for rotatably supporting said cylinder and axially moving the same, means for engaging said groove to cause rotation of said cylinder as it is moved axially by said first means and for seating the rack in the groove and displacing desired portions thereof to rigidly secure the rack to said cylinder, and means mounted on said first means for resiliently causing said cylinder to rotate to aid in maintaining said groove and that portion of the rack being inserted therein in proper relative relationship.

WILLIAM F. BRÜGMANN.
